CLAIM

The ornamental design for a random generator of numbers device, as shown and described.

DESCRIPTION

FIG. 1 is a front elevational view of a random generator numbers device showing my new design;

FIG. 2 is a side elevational view thereof;

FIG. 3 is a bottom plan view thereof;

FIG. 4 is a top plan view thereof; and,

FIG. 5 is an isometric view thereof showing my design.

1 Claim, 3 Drawing Sheets

FIG. 3

FIG. 4

FIG. 5
